UNITED STATES PATENT OFFICE

2,555,991

FLOOR RACK

Arthur F. O'Connor, Chicago, Ill., assignor to
 Union Asbestos & Rubber Company, a corpora-
 tion of Illinois

Application September 28, 1946, Serial No. 700,077

4 Claims. (Cl. 105—375)

1

This invention relates to floor racks and more particularly to lading supporting racks of the type used in railway refrigerator cars and the like.

One of the objects of the invention is to provide a floor rack which resiliently supports the lading to absorb vertical shocks due to operation over rough track or at high speed.

Another object is to provide a lading supporting rack in which the vertical loads are carried by levers resiliently biased in a direction to urge the lading upward. According to one feature of the invention, a single spring unit may act on a plurality of levers to insure against tipping of the rack.

Still another object is to provide a floor rack in which stringers are supported on the floor of the car or a plurality of spaced base blocks. This cheapens and lightens the construction and provides a more open structure for circulation of air and drainage of liquid.

The above and other objects and advantages of the invention will be more readily apparent from the following description when read in connection with the accompanying drawing in which—

Figure 1 is a side elevation of a floor rack with parts broken away and in sections;

Figure 2 is a transverse section on the line 2—2 of Figure 1; and

Figure 3 is a section on the line 3—3 of Figure 1.

The rack of the present invention may be mounted in any conventional type of car having a floor sheet indicated at 10, and a side wall 11 supported by a longitudinally extending beam 12. The floor rack comprises a plurality of rack sections, each of which is formed by two or more parallel stringers each extending the full length of a rack section and across which slats are carried to support the lading.

As shown, each of the stringers comprises three base blocks 13, 14, and 15 which are adapted to rest on the floor of the car. An inverted channel-shaped supporting strip 16 fits slidably over the base blocks for vertical movement thereon. A slat structure 17 formed by a plurality of inverted channels extends across the supporting strips and may be secured thereto by welding or the like. It will be understood that the slats 17 are preferably perforated for circulation of air therethrough and around the lading.

The supporting strip 16 of each stringer is urged upward relative to the base blocks by a pair of levers 18. As best seen in Figure 1, the

2

levers 18 are pivoted at their outer ends to the base blocks 13 and 15 at points 13' and 15' respectively and are joined intermediate their ends to the strip 16 by cross pins 19. The levers are of such a length that their free ends will overlap slightly, and they are preferably connected by a pin 21 slidable in slots 22 in the end portions of the levers. A string 23 acts between the center base block 14 and the pin 21 to urge the free ends of the levers upward.

Each of the supporting strips 16 extends the full length of a rack section to tie together securely the slats of the section. For relatively short rack sections as shown in Figure 1 the base blocks 13 and 15 may lie adjacent the ends of the supporting strip 16 with the block 14 at the strip center. For extremely long rack sections it may be desirable to duplicate the base block, lever and spring structure adjacent each end of each supporting strip to avoid making the length of levers 18 excessive.

With this construction, the supporting strip 16 is carried on the pins 19 and is urged upward with equal force at spaced points in its length. Due to connection of the levers, the supporting strip will be kept level at all times so that the rack structure and the lading cannot tilt. As the rack is loaded, the spring 23 will be compressed allowing the strip 16 to move downward so that the lading will be resiliently supported to absorb vertical shocks. Upward movement of the strip on the base blocks may be limited by bolts 24 extending through vertical slots in the end blocks 13 and 15 and by bolts 25 extending through upwardly projecting loops 26 on the center base block 14.

In order that the rack can be swung up to facilitate cleaning of the car floor, it is pivoted to the car side wall. As shown, a bracket 27 secured to one of the supporting strips 16 carries a pin 28 which is slidable and rotatable in a slot 29 in a hinge bracket 31. With this construction, the supporting strips and slat structure can move vertically without interference from the hinge and the entire rack can be swung about the pin 28 to a vertical position at the side of the car to permit cleaning of the car floor.

While one embodiment of the invention has been shown and described in detail, it will be understood that this is illustrative only and is not to be taken as a definition of the scope of the invention, reference being had for this purpose to the appended claims.

What is claimed is:

55 1. In a floor rack for a railway car or the like,

a stringer comprising base means, an inverted channel-shaped supporting strip slidable vertically over the base means, a lever pivoted at spaced points in its length to the base means and the channel-shaped strip, and a spring acting on the base means and a third point on the lever spaced from its pivotal connection to the base means and the strip to urge the lever in a direction to raise the strip on the base means.

2. In a floor rack for a railway car or the like, 10 a stringer comprising an inverted channel-shaped supporting strip, a plurality of base blocks fitting slidably in the strip, means to limit vertical movement of the blocks relative to the strip, a lever pivoted at spaced points to the strip and to one of the blocks, and a spring engaging another block and the lever and urging the lever in a direction to move the blocks downward relative to the strip.

3. A floor rack for a railway car or the like 20 comprising a plurality of parallel stringers and slats crossing and secured to the stringers, each of the stringers comprising base means, an inverted channel-shaped supporting strip slidable over the base means and to which the slats are secured, means to limit relative vertical movement of the strip and the base means, a lever pivoted at spaced points to the strip and the

base means, and a spring engaging the base means and the lever and urging the lever in a direction to raise the strip relative to the base.

4. A floor rack for a railway car or the like 15 comprising a plurality of parallel stringers and slats crossing and secured to the stringers, each of the stringers comprising base means, an inverted channel-shaped supporting strip slidable over the base means and to which the slats are secured, means to limit relative vertical movement of the strip and the base means, a pair of levers pivoted at spaced points to the strip and the base means with their free ends extending toward each other, and a spring engaging the free ends of the levers and the base means and urging the levers in a direction to raise the strip relative to the base.
